SAMUEL HUTCHINSON, OF LEEDS, ENGLAND.

Letters Patent No. 102,270, dated April 26, 1870.

IMPROVEMENT IN MACHINERY FOR STRIKING OUT LEATHER.

The Schedule referred to in these Letters Patent and making part of the same.

To all whom it may concern:

Be it known that I, SAMUEL HUTCHINSON, of Leeds, in the county of York and Kingdom of England, have invented new and improved Machinery or Apparatus for "Striking Out Leather;" and I do hereby declare that the following is a full and exact description thereof, reference being had to the accompanying drawings and to the letters of reference marked thereon.

This invention relates to means of effecting what is technically known as "striking out" or stretching and straightening skins in the process of leather-dressing; and

The improvements consist in the combination of a plain, even-surfaced roller, having a recess therein and a slip-rod and fastener to hold a skin when placed on the said roller, with a spirally-fluted roller, the spirals of which run in opposite directions from the middle thereof. These rollers are caused to rotate at different surface-speeds, the plain one to carry the skin and the fluted one to operate upon it to strike out, stretch, or expand and straighten the same, for which purpose it is run at a greater surface-speed than the plain one. The said rollers are mounted in suitable frame-work, and may be driven by gearing, pulleys, and straps, or equivalent means, from any convenient source of motive-power, or by manual power.

This invention will be readily understood by reference to the accompanying sheet of drawings, wherein—

Figure 1 is the front elevation, and

Figure 2 is an end elevation of a machine constructed in accordance therewith.

A is the plain-surfaced roller, having a recess in which is a slip-rod, *a*, held by a screw-bolt, *a'*. This roller is mounted in stationary bearings of the frame-ends B, which are held together by the tie-rods *B'*, secured by screw-nuts.

C is the spirally-fluted roller, mounted in bearings capable of being moved up or down in the said end-frames, so that its surface may be adjusted or set nearer to or further from the surface of the plain roller, as required, which adjustment is effected by means of the cross-shaft D and the winch-handle *D'*, bevel-wheels *D''* and *D'''* connecting the same with the

screw-pins *D⁴* and *D⁵* attached to the bearings of the said roller.

On one end of this fluted roller are the driving-pulleys E and E', and on the other end is a worm, F, in gear with a wheel, F', loose on an upright shaft, G, on which is fixed a worm, G', in gear with a wheel, H, fixed on the end of the shaft of the roller A.

On the top of the shaft G is a slidable clutch, I, movable on a feather in the said shaft by the handle J, which is hinged on a pillar, K, so as to place it in or out of gear with another clutch on the wheel F', whereby, when in gear, a slow motion is communicated from the roller C to the roller A.

The method of using this machine is as follows:

A bolster of India rubber and another of leather are first fixed; each by one edge, in the recess of the roller A, and are loose at the other edges, so that, as the said roller is turned, they become wound tight thereon. The India rubber, being elastic, will yield to the inequalities in the substance of the skin when placed thereon to be operated by the fluted roller.

It will now readily be seen that, if the skin be placed with its rig, or about its middle from neck to butt, or acrosswise thereof from belly to belly, under the slip-rod in the recess, and the rod secured by the screw-bolt so as to hold the said skin thereon, and, motion being given to the rollers in the proper direction, the skin will pass in betwixt them, when the spiral flutings of the roller C, diverging from the middle, will strike out or stretch the said skin on one side of the rod during its passage, and thereby straighten or make it even, ready for the process of shaving or other purpose. It is then changed, and the other side of the skin is operated upon in like manner.

What I claim as my invention is—

The combination of a plain roller, having provision for fastening a skin thereto, with a vertically-adjustable spirally-fluted roller, arranged and used in manner and for purposes substantially as shown and described.

SAMUEL HUTCHINSON.
